(57) **CLAIM**

The ornamental design for a container for hair care composition, as shown and described.

DESCRIPTION

FIG. 1 is a perspective view of a container for hair care composition, embodying our new design;

FIG. 2 is a front view of the container for hair care composition of FIG. 1;

FIG. 3 is a first side view of the container for hair care composition of FIG. 1;

FIG. 4 is a back side view of the container for hair care composition of FIG. 1;

FIG. 5 is a top view of the container for hair care composition of FIG. 1; and,

FIG. 6 is a bottom view of the container for hair care composition of FIG. 1.

The broken lines shown in the drawings are for illustrative purposes only and form no part of the claimed design. Our design resides in a container for a hair care composition wherein certain portions are opaque and certain portions are transparent. Conventional transparency shading is utilized for the transparent portions.
